UNITED STATES PATENT OFFICE.

WILLIAM W. JACKSON, OF PHILADELPHIA, PENNSYLVANIA, ASSIGNOR TO
THE MACKELLAR, SMITHS & JORDAN COMPANY, OF SAME PLACE.

DESIGN FOR A FONT OF PRINTING-TYPE.

SPECIFICATION forming part of Design No. 17,342, dated May 10, 1887.

Application filed February 25, 1887. Serial No. 238,894. Term of patent 7 years.

To all whom it may concern:

Be it known that I, WILLIAM W. JACKSON, (assignor to the MACKELLAR, SMITHS & JORDAN COMPANY,) of the city and county of Philadelphia, Pennsylvania, have invented and produced a new and original Design for a Font of Printing-Type, of which the following is a specification.

The nature of my design is clearly shown in the accompanying typographic impression, to which reference is made; and it consists of an unshaded letter ornamented by the curved line with dot termination, found in the A, B, D, F, H, I, K, M, N, P, R, T, X, and Y at the base of the letters, the curved line curling to the right and followed by the dot termination, in the C, E, F, and G extending from the upper right-hand portion of the letter, and in the V and W extending to the left from the upper right-hand termination. The cross ornaments of the A and H consist of inclined lines meeting at a central point. The character of the design is preserved in the lower case, the logotypes, and numerals.

In connection and for use with the capitals and lower-case are shown three typographic adjuncts. The first consists of a center composed of a light inclined line, a heavy inclined line, followed by a light inclined line. Extending upward upon the left of this central figure is the curved line curving to the left and having the dot termination, and downward upon the right of this central figure the curved line curving to the right and having the dot termination; the second consisting of a square with heavy central line, from each side of which proceeds the light curved line with heavy triangular termination, and between these curved lines, and extending from about the center of the square figure, a spear-head-like ornament; the third consisting of an oblong figure with heavy central line, from each side of which proceeds the light curved line with dot termination, between which extend to the right a series of dots gradually diminishing in size.

Having now described my invention, I claim—

The design for a font of printing-type, as herein shown and described, the same consisting of an unshaded letter ornamented by the curved line with dot termination, as found in the A, B, D, F, H, I, K, M, N, P, R, T, X, and Y at the base of the letters, the curved line curling to the right and followed by the dot termination, in the C, E, F, and G extending from the upper right-hand portion of the letter, and in the V and W extending to the left from the upper right-hand termination, the cross ornaments of the A and H consisting of the inclined lines meeting at a central point, the character of the design being preserved in the lower-case, the logotypes, and in the numerals, as well as the three typographic adjuncts shown, the first consisting of a center composed of a light inclined line, a heavy inclined line, followed by a light inclined line, from which central figure extends upward upon the left a curved line curving to the left and having the dot termination, and downward upon the right of this central figure the curved line curving to the right and having the dot termination; the second consisting of a square with heavy central line, from each side of which proceeds the light curved line with heavy triangular termination, and between these curved lines, and extending from about the center of the square figure, a spear-head-like ornament; and the third consisting of an oblong figure with heavy central line, from each side of which proceeds the light curved line with dot termination, between which extend to the right a series of dots gradually diminishing in size.

WM. W. JACKSON.

In presence of—

CHAS. F. TYER,
SAM'L. B. VAN DUSEN.
